UNITED STATES PATENT OFFICE.

OSWALD CORADI, OF ZURICH, SWITZERLAND.

ELECTRIC FURNACE.

Application filed January 10, 1923. Serial No. 611,803.

To all whom it may concern:

Be it known that I, OSWALD CORADI, a citizen of the Republic of Switzerland, residing at Zurich, Switzerland, have invented 5 certain new and useful Improvements in Electric Furnaces, of which the following is a specification, reference being had therein to the accompanying drawing.

The known electric furnaces of the resistance type having a resistor of granular carbonaceous material, which, for instance, are described in "Der elektrische Ofen im Dienste der keramischen Gewerbe und der Glas- und Quartzglaserzeugung," by J. 10 Brönn, Halle a. S., 1910, Monographien über angewandte Elektrochemie, vol. 34, present the following disadvantages:

The current consumption in known furnaces is comparatively high, as the bulky 20 mass of the resistor, which shows the same temperature in all points of its cross-sectional area, has a large outer surface in comparison with the inner surface surrounding the heating chamber, so that the radiation of 25 heat towards the outside is 1.5 to 2 times as large as the useful heat transmission towards the heating chamber; further in vertical furnaces, in which the resistor exceeds a given height, the resistance is not uniform owing 30 to the influence of the weight of the upper parts of the resistor on the lower part, the lower parts of such a vertical furnace are therefore heated in a higher degree than the upper parts and a uniform temperature 35 throughout a comparatively large heating chamber can therefore not be attained.

Electric furnaces for heating, tempering and smelting purposes have already been proposed (vide U. S. A. patent specification No. 40 1,335,199, French specification No. 329,822/5,508 and German specifications No. 153,100 and 201,202) in which the electrodes through which the current is supplied are so arranged that the path of the current is 45 parallel to the circumference of the cross-section of the heating chamber, for instance a muffle; however, these known furnaces present the disadvantage of being hotter in their lower part than in their upper part, 50 which is a great drawback in furnaces for heating steel or for baking porcelain, ceramics, etc. A thoroughly uniform temperature is reached with the furnace according to the present invention in which the circumferences of the cross-sectional areas of 55 the chamber to be heated, or the muffle re-

spectively, or the length of the path of the current are varied in accordance with the varying resistances present in the resistor, which surrounds the chamber. 60

Several embodiments of the present invention are illustrated by way of example on the accompanying drawings, in which:

Fig. 1 is a vertical longitudinal section along line I—I of Fig. 2 of a first constructional example. 65

Fig. 2 is a cross-section along line II—II of Fig. 1.

Fig. 3 is a horizontal section through a second constructional example. 70

Fig. 4 shows a vertical section of a third constructional example and

Fig. 5 is a horizontal section along line V—V of Fig. 4.

Figs. 6 and 7 illustrate a fourth constructional example in sections along line VI—VI of Fig. 7 and VII—VII of Fig. 6 respectively, 75

Fig. 8 is a vertical section along line VIII—VIII of Fig. 9 of a fifth constructional example. 80

Fig. 9 is a horizontal section along line IX—IX of Fig. 8 and Fig. 10 is a vertical section along line X—X of Fig. 9.

Fig. 11 is a modification of a detail of 85 Fig. 8.

Referring to the furnace illustrated in Figs. 1 and 2, 1 denotes a base plate, on which the upright walls 3 are supported. The walls consist of the ordinary refractory 90 material, for instance fire-clay, and enclose a hollow chamber, in which a muffle 2 is inserted. The annular space between the muffle 2 and the vertical walls 3 is filled with a more or less finely divided carbonaceous 95 material 7, the resistor acting as resistance. Into the resistor there are inserted two electrodes 5 and 6 insulated from each other by means of a block 4 of refractory material. These electrodes extend over the whole 100 height of the resistor and over the whole width of its cross-section, i. e., from the wall 2 of the muffle to the vertical wall 3 of the furnace. The furnace is covered by an annular plate 8 provided with a central opening that corresponds to the free cross-sectional area of the muffle. This opening is closed by a plate 9 of refractory material. The electrodes 5 and 6 may consist of iron, in case high temperatures have to be obtained they are preferably made of carbon. 110 When the current is cut in the resistor is

heated, which heat is transmitted to the jacket of the muffle, from where the further transmission of heat to the interior of the muffle takes place. It is a well known fact 5 that the electric current has the tendency to choose the shortest path, therefore the carbonaceous particles in contact with the muffle forming the shortest path will be heated to the greatest extent. The heat in 10 the resistor mass 7 decreases towards the outside in accordance with the increasing path of the current, so that the carbonaceous particles in contact with the inner side of the wall 3 of the furnace remain much 15 cooler than the particles adjacent to the muffle 2. In this way the heat losses by radiation towards the outside are correspondingly smaller and the heat can be raised to the limit which the material of the 20 muffle will stand without the outer face of the furnace walls and the cover plates 1 and 8 being subjected to the same high degrees of heat, as is the case with known furnaces of the resistance type. This fact ensures 25 an important saving in energy and a considerable increase in the life of a furnace.

With the furnace illustrated in Figs. 1 and 2 a uniform temperature within the muffle 2 is ensured owing to the shape of 30 the muffle. The muffle 2 has at its lower end a larger circumference than at its upper end. If now this increase in the circumference corresponds to the decrease in the resistance in the vertical direction the muffle 35 is uniformly heated in every part of its height which is an indispensable requirement with furnaces for heating, case hardening and tempering or annealing purposes. With furnaces of this type a uniform temperature 40 within the chamber to be heated, i. e., within the muffle 2, is absolutely necessary, whereas with ordinary furnaces for smelting purposes differences in temperature between the upper and the lower parts 45 of the resistor can be neglected.

Fig. 3 shows a furnace according to the invention provided with three electrodes and adapted to be worked with three phase current.

50 In Figs. 4 and 5 a heating furnace is illustrated which is of a rectangular section in a horizontal plane and in which the heat insulating material surrounding the furnace is provided with a lateral opening 10 in 55 order to permit the placing of the objects to be treated into the furnace.

A horizontal furnace is illustrated in Figs. 6 and 7 in which the cylindrical muffle 2 is arranged eccentrically in the cylindrical resistor 7, in order to compensate for the difference in the resistance occurring through the lower part of the mass of the resistor being compressed by the weight of the upper parts of the resistor.

65 Figs. 8, 9 and 10 represent a furnace of

the channel type to various points of which current is supplied by means of electrodes 5 and in which furnace in order to attain a uniform temperature in all the points of the chamber 11 to be heated the cross-sectional area of and the lengths of the paths of the current in the various horizontal layers of the resistor are so dimensioned that all the horizontal layers have the same resistance in spite of the differing density of the material. Two adjacent electrodes of the furnace illustrated in Figs. 8-10 may also be united to form one single electrode 12 as is shown in Fig. 11.

I claim:

1. In an electric furnace of the resistance type, a resistance element consisting of a loosely piled up material, the cross-sectional areas and the lengths of the path of the current in the different horizontal layers of the material being so chosen that all these horizontal layers of material present approximately the same resistance so that a uniform temperature will be attained in a chamber to be heated.

2. In an electric furnace of the resistance type, a resistance element consisting of a granulous carbonaceous material, the cross-sectional areas and the lengths of the path of the current in the different horizontal layers of the material being so chosen, that all these horizontal layers of material present approximately the same resistance so that a uniform temperature will be attained in a chamber to be heated.

3. In an electric furnace of the resistance type, a resistance element consisting of a granulous carbonaceous material the cross-sectional areas and the lengths of the path of the current in the different horizontal layers of the material being so chosen by arranging for the lengths of the circumference of a chamber to be heated and of the resistance element in such a way that all these horizontal layers of material present approximately the same resistance so that a uniform temperature will be obtained in a chamber to be heated.

4. In an electric furnace of the resistance type, the combination with a shell of refractory material, of a shell of heat transmitting material, and a resistance element consisting of a granulous carbonaceous material filled into the intermediate space between said two shells, the shape of said shells being so chosen that cross-sectional areas and length of path of the current result in the different horizontal layers of resistance element that all these horizontal layers of material present approximately the same resistance so that a uniform temperature will be attained in a chamber to be heated.

5. In an electric resistance furnace having a furnace chamber; a resistor of loosely piled material surrounding the chamber,

and electrodes contacting with the resistor, the shape of the resistor and cross-sectional dimensions being chosen to present current paths in all horizontal layers of substantially the same resistance to produce a uniform temperature throughout the furnace chamber.

6. In an electric resistor furnace having a furnace chamber; a resistor of loose material surrounding the chamber, and electrodes contacting with the resistor, the cross-section of the resistor varying uniformly to produce a uniform resistance in substantially all horizontal layers.

7. In an electric resistance furnace having a furnace chamber, a resistor surrounding said chamber and decreasing in cross-section from the bottom to the top of the chamber.

8. In an electric resistance furnace having a furnace chamber, a resistor surrounding said chamber, electrodes contacting with said resistor at its maximum longitudinal section and the resistor uniformly decreasing in section from the bottom to the top thereof.

In testimony whereof I affix my signature.

OSWALD CORADI.
